INVENTOR:

Halsey M. Larter,
By
Russell M. Everett,
ATTORNEY.

UNITED STATES PATENT OFFICE.

HALSEY M. LARTER, OF NEWARK, NEW JERSEY, ASSIGNOR TO LARTER & SONS, OF NEWARK, NEW JERSEY, A FIRM COMPOSED OF FREDERICK H. LARTER, HARRY C. LARTER, AND HALSEY M. LARTER.

KNIFE.

1,274,288.

Specification of Letters Patent. Patented July 30, 1918.

Application filed October 22, 1915. Serial No. 57,242.

To all whom it may concern:

Be it known that I, HALSEY M. LARTER, a citizen of the United States, and a resident of Newark, in the county of Essex and State 5 of New Jersey, have invented certain new and useful Improvements in Knives, of which the following is a specification.

This invention relates more particularly to clasp knives such as are intended to be 10 carried in the pocket, and the objects of the invention are to form a combined handle and casing; to provide a construction by which two hinged leaves or sections form a casing for the knife when the blades are 15 closed, and form a handle when the blades are opened; to enable the blades to be hinged after the usual manner of a penknife; to secure a construction by which the blades may be closed without any special manipula- 20 tion of the leaves or sections of the casing; to provide means for holding the leaves or sections in proper relation to each other and to the rest of the knife when both in closed position and in open position; to avoid separable parts which are liable to become lost; 25 to secure compactness and simplicity, and to secure other advantages and results as may be brought out in the following description.

Referring to the accompanying drawing, 30 in which like numerals of reference indicate the same parts throughout the several views,

Figure 1 is a side view of a knife of my improved construction;

Fig. 2 is an end view of the same;

35 Figs. 3 and 4 are cross-sections taken on lines A—A and B—B respectively, of Fig. 1;

Fig. 5 is a cross-section corresponding to Fig. 4 with the case sections or leaves opened;

40 Fig. 6 is a longitudinal section on line C—C Fig. 4;

Fig. 7 is a top edge view, and

Fig. 8 is a detail section on line D—D, Fig. 6.

45 In the specific embodiment of the invention shown in said drawing, 1, 2 indicate case sections or leaves which when closed together form a case of approximately the size and shape of a knife and which incloses the 50 working parts thereof, as shown in the drawings. To this end the said sections have each a low bezel 3, or 4, the bezel of one section as 3 being provided with a stepped lip 5 to close into the other bezel 4 and form

a tight joint. At the side of the case from 55 which the blades emerge in opening, each bezel is notched as at 6 so that the thumb nails of the user can engage each one of the sections to open the same, and at the opposite edge of the case the sections are hinged together as at 7. Furthermore, this hinge is provided with a spring 8 which serves to hold the sections closed tightly together and also when they have been opened past a certain point to hold them in extreme 60 opened position, as is common in eyeglass cases and the like. In illustrating this, I have shown the flat leaf spring 8 fixed at one end to the beveled side of a block 20 on one of the hinged sections or leaves, as 2, see 65 Fig. 6, and pressed flatwise at its other free end against the corresponding beveled side of a block 21 fast to the other section or leaf 1, when the case is closed, see Figs. 4 and 6. When the case is open the free end of said 70 spring 8 lies against the other beveled surface of the block 21, as shown in Fig. 5. Any other suitable means might be employed, however.

The blade-carrying portion of the knife 80 lies between the two case sections or leaves 1, 2 and is suitably secured thereto to hold it in proper relative position, as by hinging it to the same hinge pin 7 which connects the sections or leaves. I have shown the 85 blade-carrying portion as comprising opposite plates 9, 9 between which the blades 10, 11 are pivoted, said plates being joined at their bottom by a back-piece 12 which carries at its outer side sleeves or pieces of hollow wire 13 to receive the hinge pin 14 and has at its inner side a spring 15 to operate the blades as is common in the art. When the blades are closed as shown in Fig. 1, both they and their carrying portion lie neatly 90 and compactly within the case sections or leaves, and upon opening said sections or leaves, the blades can readily be opened in the usual manner of pocket knives.

Apertures 16 are provided in the ends of 100 the case for allowing the blades to project and the case sections or leaves 1, 2 to close tightly together at the same time, said apertures being shown as provided by cutting away portions of the bezels as at 17, 18, see 105 Figs. 2 and 5 more especially. The case thus forms a handle for grasping to use a blade when open, and preferably the con-

struction is such that the blade can be closed without any necessity for opening the case sections or leaves 1, 2 with the fingers. For this purpose, the apertures 16 in the ends of 5 the case taper toward the front edge of the knife or edge from which the blades open, so that the tang of the blade which lies in said aperture when the blade is open will force the sections or leaves apart as the blade 10 is closed. This greatly expedites closing of the knife, since simply closing the blade automatically operates the case sections or leaves. This construction enables the knife when open to be closed just like any pocket 15 clasp knife, by shutting the blade, since the tang of the blade will operate the sections or leaves of the case enough to make a passage for the blade to go through into closed position, and then the spring which holds 20 said sections or leaves together will instantly shut them tightly together. It will be understood that the point to which the sections or leaves must be opened to cause their 25 spring to throw them into wide open position is beyond that to which the blade forces them apart in closing.

Obviously the upper or inner edge of the tang 19 of the blade may be beveled or wedge-shaped, as desired, to assist in the 30 smooth operation of the case leaves or sections, and it will be noted that the tang engages at its lower or back edge the bottom of the aperture 16 in the case, as a stop, and which may thus reinforce the blade against 35 the strain or tendency of use to bend it backward.

While I have shown a knife having two blades, for purposes of illustration, it will be understood that any number of blades 40 may be employed from one up, and I do not desire to restrict myself in this respect. It will be understood that various other detail modifications and changes can be made in the manufacture of my improved knife, by 45 those skilled in the art, without departing from the spirit and scope of the invention, and I do not wish or intend to limit myself herein except as required by the following claims when construed in the light of the 50 prior art.

Having thus described the invention, what I claim is:

1. In a knife, the combination of opposite case sections or leaves adapted to fold together and provide an interior chamber, said sections or leaves being hinged at one longitudinal edge and adapted to close together at the opposite edge, a blade-carrying portion between said sections or leaves and pivoted thereto adjacent their hinged edges, and a blade mounted in said blade-carrying portion to swing in the plane of the sections or leaves when closed.

2. In a knife, the combination of opposite case sections or leaves adapted to fold to-

gether and provide an interior chamber, said sections or leaves being hinged at one longitudinal edge and adapted to close together at the opposite edge, a blade-carrying portion between said sections or leaves and pivoted thereto adjacent their hinged edges, and a blade mounted in said blade-carrying portion to swing in the plane of the sections or leaves when closed.

3. In a knife, the combination of opposite case sections or leaves adapted to fold together and provide an interior chamber, said sections or leaves being hinged at one longitudinal edge and adapted to close together at the opposite edge, a blade-carrying portion between said sections or leaves and pivoted upon the same hinge pin therewith, and a blade mounted in said blade-carrying portion to swing in the plane of the sections or leaves when closed.

4. In a knife, the combination of opposite case sections or leaves adapted to fold together and form an interior chamber, said case sections or leaves being hinged together at one longitudinal edge and adapted to close together at the other edge, a blade-carrying portion open at one edge between said sections or leaves and pivoted thereto by its closed edge adjacent their hinged edges, and a blade mounted in said blade-carrying portion to swing into and out of the same through its said open edge.

5. In a knife, the combination of opposite case sections or leaves adapted to fold together and provide an interior chamber, said sections or leaves being hinged at one longitudinal edge and adapted to close together at the opposite edge, means for normally holding said sections or leaves either closed or wide open, a blade-carrying portion between said sections or leaves and pivoted thereto, and a blade in said blade-carrying portion adapted to swing in the plane of the sections or leaves when closed.

6. In a knife, the combination of opposite case sections or leaves adapted to fold together and form an interior chamber, said sections or leaves being hinged at one longitudinal edge and adapted to close together at the other edge, a blade-carrying portion between said sections or leaves and secured thereto, and a blade in said blade-carrying portion pivoted to swing in the plane of the sections or leaves when closed and project from the end thereof, said sections providing at one end of the case an opening for said blade which is tapered at its end toward the free edges of the sections or leaves, whereby the blade will automatically separate said sections or leaves in closing.

7. In a knife, the combination of opposite case sections or leaves adapted to fold together and provide an interior chamber, said sections or leaves being hinged at one longitudinal edge and adapted to close to-

gether at the opposite edge, means for normally holding said sections or leaves either closed or wide open, a blade-carrying portion between said sections or leaves and se-
5 cured thereto, and a blade in said blade-
carrying portion adapted to swing in the
plane of the sections or leaves when closed
and to project from the end thereof, said
sections being recessed at one end to form
10 an opening for said blade which opening is
tapered or wedge-shaped at its end toward
the free edges of the sections or leaves,
whereby the blade will automatically sepa-
rate said sections or leaves in closing.
15 8. In a knife, the combination of oppo-
site case sections or leaves adapted to fold
together and provide an interior chamber,
said sections or leaves being hinged at one
longitudinal edge and adapted to close to-
20 gether at the opposite edge and providing
at their meeting edges a recess at one end
of the case, means for resiliently holding
said sections or leaves closed together, a
blade-carrying portion between said sec-
25 tions or leaves and connected thereto ad-
jacent their hinged edges, and a blade
mounted in said blade-carrying portion to
swing between the free edges of the case sec-
tions or leaves in the plane thereof when
30 closed and project through the said end
aperture, the tang of said blade at the cut-
ting edge of the blade and the adjacent wall
of the aperture being one inclined with re-
spect to the plane of swinging of the blade
35 so that said blade will wedgingly open the
case sections or leaves and close them.
9. In a knife, the combination of opposite
case sections or leaves adapted to fold to-
gether and provide an interior chamber,
40 said sections or leaves being hinged at one
longitudinal edge and adapted to close to-
gether at the opposite edge and providing
at their meeting edges a recess at one end of
the case, means for resiliently holding said
45 sections or leaves closed together, a blade-
carrying portion between said sections or

leaves and connected thereto adjacent their
hinged edges, and a blade mounted in said
blade-carrying portion to swing between the
free edges of the case sections or leaves in 50
the plane thereof when closed and project
through the said end aperture, the back of
said blade and the adjacent wall of the
aperture being so positioned with respect
to each other that they engage when the 55
blade is open, whereby said blade is rein-
forced against backward strain.

10. In a knife, the combination of oppo-
site case sections or leaves adapted to fold
together and provide an interior chamber, 60
said sections or leaves having at one pair
of edges alined sleeves and at their other
edges finger means for separation, a pivot
extending through said sleeves, a blade-
carrying portion in said interior chamber 65
formed by the case sections, said blade-car-
rying portion having on its back exterior
sleeves alining with the said sleeves on the
case sections and receiving the same pivotal
pin, and a blade mounted in said blade-car- 70
rying portion to swing in the plane thereof
toward and away from the line of hinging of
said parts.

11. In a knife, the combination of oppo-
site case sections or leaves adapted to fold 75
together and provide an interior chamber,
said sections or leaves having at one pair of
edges alined sleeves and at their other edges
finger means for separation, a pivot ex-
tending through said sleeves, a blade-carry- 80
ing portion in said interior chamber formed
by the case sections, said blade-carrying
portion having on its back exterior sleeves
alining with the said sleeves on the case sec-
tions and receiving the same pivotal pin, 85
a blade mounted in said blade-carrying por-
tion to swing in the plane thereof toward
and away from the line of hinging of said
parts, and spring means for holding case
sections or leaves shut or closed together.
